DESIGN FOR PLIERS

Donald G. Morse, Boston, Mass.

Application May 24, 1932, Serial No. 43,890

Term of patent 14 years

To all whom it may concern:

Be it known that I, DONALD G. MORSE, a citizen of the United States of America, residing at Boston, county of Suffolk, and State of Massachusetts, have invented a new, original, and ornamental Design for Pliers, of which the following is a specification, reference being had to the accompanying drawing, forming part thereof:

Fig. 1 is a face view of the pliers showing my new design; and

Fig. 2 is a side view thereof.

I claim:

The ornamental design for pliers as shown. In witness whereof I have signed this specification this 19th day of May, 1932.

DONALD G. MORSE.
